(57) CLAIM

The ornamental design for a wallet, as shown and described.

DESCRIPTION

1. Wallet

1.1 : Perspective

1.2 : Front

1.3 : Back

1.4 : Right

1.5 : Left

1.6 : Top

1.7 : Bottom

1.8 : Open perspective view

The present design relates to a foldable wallet; in the closed condition the wallet, seen in front or rear view, has an essentially rectangular shape; a lozenge-shaped ornamental element is affixed to the lower right-side corner portion of the front face of the wallet; in the inside the wallet has an upper larger compartment or pocket, which extends horizontally across the entire length of the wallet; under said upper pocket in each half of the wallet there is provided a respective plurality of smaller pockets having decreasing heights and characterized by their upper edge which is partly horizontal and partly oblique.
